UNITED STATES PATENT OFFICE.

HENRY GARANT, OF CHATTANOOGA, TENNESSEE, ASSIGNOR OF ONE-HALF TO W. B. DAVIS,
OF CHATTANOOGA, TENNESSEE.

DIAL KNITTING-MACHINE.

No. 878,792.

Specification of Letters Patent.

Patented Feb. 11, 1908.

Application filed June 14, 1906. Serial No. 321,719.

To all whom it may concern:

Be it known that I, HENRY GARANT, a citizen of the United States of America, and resident of Chattanooga, county of Hamilton, State of Tennessee, have invented certain new and useful Improvements in Dial Knitting-Machines, of which the following is a full and clear specification, reference being had to the accompanying drawing, in which—

Figure 1 is a side elevation showing my device attached to a circular knitting machine of well known type, my invention being shown in full lines and the machine proper being shown in dotted lines; Fig. 2 a perspective view of mat attachment detached; Fig. 3 a plan view thereof; Fig. 4 a side elevation thereof; Fig. 5 a detail perspective of the cam for lifting the projecting ends of the horizontal needles; and Fig. 6 a detail view partly in section of the adjustable screw tappet for lifting the cam plate shown in Fig. 5.

My invention relates to that class of knitting machines for producing ribbed work, which employ two sets of needles, one set working horizontally and the other set vertically, and means being provided to automatically effect the production of slack courses in the tubular fabric, so that the ribbed tube may be severed into lengths and be used for the tops of half-hose, cuffs for shirts and drawers, etc.

The object of my invention is to provide an extremely simple attachment whereby this loose or slack course will be made much larger, and to effect this I provide means whereby the horizontal needles will be elevated simultaneously with the depression of the vertical needles, thereby drawing the loops out in opposite directions and consequently materially enlarging the slack course, as more fully hereinafter set forth.

Referring to the drawings by reference characters, A is the fixed frame or bed of the machine, B the fixed cylinder for the vertical needles, and D the fixed circular dial carrying the horizontal needles.

E is the rotating cam ring for operating the vertical needles, and F the rotating cam plate for operating the horizontal needles, the ring E being driven by suitable bevel gearing from the driving shaft in the usual manner, and the cam plate F being suspended from and adapted to rotate with the arch E' of the cam ring E.

C is the usual cam which is adapted to be raised automatically when the loose course devices are to be brought into play. When raised, this cam C is adapted to actuate tappet G and thereby, through gears H, actuate shaft I and swing arm J inward until its screw K strikes lever L and thereby, in the well known manner, throw into action the devices for drawing down the vertical needles as the ring E rotates to produce the slack course.

All the foregoing devices are common to circular dial machines and they need not be more fully described herein.

The wave-like movement of the vertical needles is indicated by the heavy dotted line M, and the movement of the horizontal needles caused by my attachment is indicated by the heavy dotted line N, it being observed that at O the projecting heads of these needles are raised, this elevation of the horizontal needles being coincident with the depression of the vertical needles so that the two waves travel together around the dial. In this way I cause both sets of needles to take an active part in the drawing out of the loops forming the loose course, thus securing a wider and looser course than is possible where, as heretofore, the horizontal needles alone have been actuated to produce this slack course. I may produce this wave-like elevation of the horizontal needles by any suitable mechanism, the specific mechanism I employ being dependent upon the particular machine in which the invention is embodied.

In the type of machine I have shown I have found that the simplest way to produce this action of the horizontal needles is to tap into the upper end of screw K a tappet screw P, and arrange in the path of the upper end of said tappet an upwardly swinging plate Q which is pivotally supported on a pivot screw R and extends inwardly toward the ring B and is provided at its inner edge with a cam S whose upper cam surface is adapted to be elevated into the path of the horizontal needles when the tappet P is swung in under plate Q to lift the same. The cam carrying plate Q has its under surface beveled at Q' downwardly and inwardly so that when the upper end of tappet P is moved inward toward the ring B the cam S will be raised and held up during the rotation of the cam ring E, at the same time and coincidently with the depression of the

100 surface of the horizontal needles. The cam S is provided with a shoulder 105 which is adapted to be held up by the cam E' when the cam E is rotated, so that the cam S will be held up during the rotation of the cam ring E, at the same time and coincidently with the depression of the

vertical needles. By adjusting the screw P the length of loop may obviously be regulated. To support the plate Q in the proper position a lug Q² thereon engages a lug T carried on the bracket U which is attached to the cam ring E.

It will be obvious to those skilled in the art that various mechanical embodiments of the invention are possible and I, therefore, 10 do not wish to be limited to the exact arrangement and construction shown.

What I claim and desire to secure by Letters Patent is:—

1. In combination with a knitting machine embodying a vertical series of needles a horizontal series of needles and means for automatically actuating the vertical series of needles to produce a slack course, devices for actuating the horizontal needles to assist 20 in producing the slack course.

2. In combination with a knitting machine embodying a horizontal series of needles, means for elevating the thread-engaging ends of said needles to produce a 25 slack course.

3. In combination with a knitting machine, embodying two series of needles, means for coincidently separating the needles to produce a slack course, these means 30 embodying devices whereby both series of needles are actuated in opposite directions simultaneously.

4. The combination in a knitting machine of the character described, of a cylinder, cylinder needles, dial needles, with means for lifting the dial needles independently of the dial to form a slack course, substantially as described.

5. The combination in a knitting machine of the character described, of the cylinder needles, the dial needles, means for actuating both the cylinder needles and the dial needles to produce a slack course, substantially as described.

45 6. The combination in a knitting machine of the character described, of a cam cylinder, needle cylinder, needles therein, dial, dial needles, a cam carried by the cam cylinder arranged to pass under the dial needles and lift them, and means for throwing the cam into and out of position, substantially as described.

7. The combination in a knitting machine of the type described, of a needle cylinder, and needles, a dial and dial needles, a cam cylinder, a shaft mounted on the cam cylinder, an arm carried by said shaft, a cam actuated by said arm for lifting the dial needles, and means for throwing the arm into 60 and out of action, substantially as described.

8. The combination in a knitting machine of the type described, of a cylinder, cylinder needles, dial and dial needles, a cam cylinder, a shaft mounted on the cam cylinder, an arm secured to the shaft, means for

throwing the arm into and out of position, a pivoted arm carrying a cam for elevating the dial needles, said arm being raised by the arm carried by the shaft, substantially as described.

9. The combination in a knitting machine of the type described, of a cam cylinder, a needle cylinder, needles carried thereby, a dial and dial needles, a slack course disk, two shafts carried by the cam cylinder, 70 said shafts being geared together, an arm on one of said shafts arranged to be actuated by the slack course disk to throw the slack course mechanism into operative position, and an arm on the other shaft arranged to be 80 actuated by the slack course disk when adjusted to another plane to throw the mechanism out of action, a cam plate connected to the mechanism for depressing the cylinder needles, and a pivoted arm, a cam carried 85 thereby for raising the dial needles, an arm carried by one of the shafts and having studs arranged to enter the spaces between the cam plate and the pivoted arm to simultaneously depress the cylinder needles and lift the dial 90 needles, substantially as described.

10. The combination in a knitting machine of the type described, of a cam cylinder, a needle cylinder, needles carried thereby, a dial, dial needles, the ends of the dial 95 needles projecting beyond the lines of the cylinder needles, and a cam acting upon the under side of the dial needles near their ends and beyond the loop so as to effect the raising of the dial needles to produce a slack 100 course, substantially as described.

11. The combination in a knitting machine of the type described, of a cam cylinder, a needle cylinder, needles therein, a dial and dial needles, a cam carried by the cam 105 cylinder, and arranged to act upon the under side of the dial needles near their ends to lift them a given distance, an arm having an adjustable stud arranged to elevate the cam when thrown into position, with means for 110 actuating the arm, substantially as described.

12. An attachment of the character described, comprising a cam element, and means for securing said elements to the cam ring of 115 a machine so that it will operate in the outer ends of the path of movement of the dial needles.

13. In an attachment of the character described, the combination with a knitting machine ring, of a dial and its needles, and a cam mounted on the ring and movable into the path of said dial needles.

14. In an attachment of the character described, the combination with a knitting machine cam ring, of a dial and its needles associated therewith, a cam mounted on the cam ring and movable into the path of the outer end of the dial needles, and means for moving 125 the cam.

15. In an attachment of the character described, the combination with a knitting machine frame, of a dial and its needles, and means for raising the outer ends of the dial needles with respect to the dial when said needles are in projected relation.

16. In an attachment of the character described, the combination with a knitting machine frame, of a dial and its needles, a swinging cam movable into the path of the outer ends of the dial needles, and means for swinging the cam into and out of such path.

17. In an attachment of the character described, the combination with a knitting machine frame, of a dial and its needles, a vertically swinging cam movable into the path of the outer end of the dial needles, and means for effecting the vertical swinging movement of said cam.

20 18. In an attachment of the character described, the combination with a knitting machine frame, of a dial and its needles associated therewith, a swinging cam movable into and out of the path of the outer ends of the dial needles, said cam having a track on its under side, and means movable along the track for vertically swinging the cam.

19. In an attachment of the character described, the combination with a cylinder, of a dial, needles mounted on the cylinder and dial, a stitch cam coöperating with the cylinder needles, and common means for simultaneously lowering the stitch cam and elevating the dial needles located thereover.

35 20. In an attachment of the character described, the combination with a cylinder, of a dial, needles movably mounted on the cylinder and dial, a downwardly movable stitch cam coöperating with the cylinder needles, an upwardly moving cam coöperating with the dial needles, and common means for simultaneously lowering the stitch cam and elevating the upwardly moving cam.

21. In an attachment of the character described, the combination with a cylinder, of

a dial, needles movably mounted on the cylinder and dial, a downwardly moving stitch cam coöperating with the dial needles, and an arm having a portion that moves between the cams for elevating one and lowering the other.

22. In an attachment of the character described, the combination with a cylinder, of a dial, needles movably mounted on the cylinder and dial, a ring frame surrounding the cylinder, a downwardly movable stem mounted in the ring frame, a stitch cam secured to the stem and coöperating with the cylinder needles, an upwardly movable cam mounted on the ring frame, and an arm pivotally mounted on the ring frame and movable between the upper end of the stem and the under side of the cam for moving the former downwardly and the latter upwardly.

23. In an attachment of the character described, the combination with a cylinder and dial, of angularly disposed needles mounted thereon, a cam ring surrounding the cylinder, a reciprocatory stem mounted on the cam ring, said stem having a stitch cam fixed to its lower portion, and a track carried by its upper end, a post secured to the cam ring, a vertically swinging cam pivoted on the post, a track carried by the cam and disposed over the track of the stem, the inner end of said cam being movable into and out of the path of the outer ends of the dial needles, a swinging arm mounted on the cam ring and having a portion movable between the tracks of the stem and cam to move one downwardly and the other upwardly, and means for swinging the arm in opposite directions.

In testimony whereof I hereunto affix my signature in the presence of two witnesses this 14 day of May 1906.
